UNITED STATES PATENT OFFICE.

ALBERT EARL CANEDY, OF CHICAGO HEIGHTS, ILLINOIS, ASSIGNOR TO THE CANEDY OTTO MANUFACTURING COMPANY, OF CHICAGO HEIGHTS, ILLINOIS.

DESIGN FOR A BLOWER AND GEAR CASING.

SPECIFICATION forming part of Design No. 35,671, dated February 4, 1902.

Application filed December 16, 1901. Serial No. 86,169. Term of patent 7 years.

To all whom it may concern:

Be it known that I, ALBERT EARL CANEDY, residing at Chicago Heights, in the county of Cook and State of Illinois, have invented and produced a certain new and useful Design for a Blower and Gear Casing, of which the following is a specification, reference being had therein to the accompanying drawings.

The design consists in the form or configuration and ornamentation of a connected blower and gear casing.

Figure 1 is a side elevation of the blower and gear casing. Fig. 2 is a reverse side view showing blower-casing. Fig. 3 is an edge or face view showing blower and gear casing.

A indicates the blower-casing in general form of a short cylinder with rounded corners, Fig. 1 showing a large central opening A' surrounded by a rim and showing rounded corners or edges B and a nozzle C projecting from one side of the casing. In the edge view,

Fig. 3, the divisional line D is shown, and bosses E project at each side of this divisional line.

Projecting from the side of the blower-casing is the short cylindrical gear-casing F, which gear-casing shows a divisional line G. Cylindrical bosses H I K project from the flat face of casing F, the boss K being longer and larger than the bosses H and I and all being grouped about the central ring or boss L, as shown in Figs. 2 and 3.

What I claim, and desire to secure by Letters Patent, is—

The design for a blower and gear casing, substantially as shown and described.

In testimony whereof I affix my signature in presence of two witnesses.

ALBERT EARL CANEDY.
